UNITED STATES PATENT OFFICE.

CHARLES ALGERNON PARSONS, STANLEY SMITH COOK, AND HERBERT GEORGE KIMBER, OF NEWCASTLE-ON-TYNE, ENGLAND; SAID COOK AND SAID KIMBER AS SIGNORS TO THE SAID PARSONS.

INTERNAL-COMBUSTION ENGINE.

Application filed August 4, 1924, Serial No. 730,011, and in Great Britain August 8, 1923.

The present invention relates to internal combustion engines and more particularly to devices suitable for starting oil engines in which the charge is ignited by the heat of 5 the compression of the combustion air in the working cylinder.

Large internal combustion engines are usually started by admitting compressed air into the working cylinder until the engine 10 has gained the necessary momentum to compress the air for combustion sufficiently to ensure the ignition of the charge.

In the use of compressed air for starting purposes there is always a risk of premature 15 explosion should the fuel be mixed with the air and the temperature be raised above the ignition point.

The object of the present invention is to obviate this danger and to use a gaseous medium under pressure which will not support 20 combustion.

The invention more particularly consists in the improvements and arrangements hereinafter described and more particularly 25 pointed out in the claims.

The invention will now be described with reference to the accompanying drawings, in which:—

Figure 1 is a section on line 1—1 of Figure 30 4 and shows the starting device fitted to a cylinder with means for regulating the compression pressure,

Figure 2 shows a modification of the means for regulating the compression pressure.

Figure 3 is a section on the line 3—3 of Figure 4, and

Figure 4 is a plan of Figure 1.

In carrying the invention into effect in one 40 form, as shown in Figures 1, 3 and 4, and taking by way of example its application to a heavy oil engine working on the four-stroke cycle the head of the working cylinder is provided with an air admission valve, A an air duct, B, leading thereto and an exhaust valve, A', the valves, A. and A', being 45 identical and operated by the rocking levers, C, C', actuated by cams mounted upon a cam shaft, D. In addition to this, a small steam 50 valve, E, is provided in the cylinder head operated by one end of a rocking lever, F, mounted upon a rotatable eccentric, G, which forms its fulcrum. This rocking lever is

provided at the other end with a roller, H, which engages with a cam, I, mounted on 55 the cam shaft, D. This eccentric may be partially rotated by means of a control lever, K, which is adapted to be moved into the "running" or into the "starting" position and is connected to the eccentric, G, by means of 60 a lever arm, L, a link, M, and a lever arm, N, fixed to the eccentric. The rotation of the eccentric moves the roller, H, of the rocking lever into or out of engagement with the cam, the "running" position being that 65 in which the rocking lever is removed from engagement with the cam, as shown in dotted lines. A suitable fuel injection valve, E', is also provided in the cylinder head and operated by the cam-shaft, D.

Where the pressure of the available steam is less than the pressure to which air is normally compressed in the working cylinder or cylinders, steam would only be admitted during that portion of the stroke when the pressure in the cylinder had fallen below the pressure of the steam. In such cases, and in cases where the steam pressure is not sufficiently in excess of the pressure to which air is normally compressed in the working cylinder, means are provided for regulating the pressure in the cylinder immediately prior to the admission of steam. This is effected by interconnecting the control lever, K, for operating the eccentric with a throttle valve, Q, situated in the air duct, B, by means of a link, O, and lever arm, P. This throttle valve is so arranged that when the control lever is moved into the "starting" position the throttle valve is closed so as to restrict 80 the passage of the air to the cylinder and the roller on the rocking lever is brought in contact with the cam. Since the air is restricted on the suction stroke the compression is consequently reduced on the compression stroke. The "starting" position is shown in full lines in Figure 1. In this position of the control lever steam will be admitted to the cylinder by the operation of the cam while a very small quantity of air 85 will only be admitted to the cylinder, due to the restriction of the throttle valve.

When the engine has been running sufficiently to gain the required momentum the control lever is thrown over to the "running" 90 position. This movement of the control

lever opens wide the throttle valve in the air duct and removes the rocking lever from contact with the cam so that further steam is not admitted to the cylinder. The engine 5 will now function in the ordinary way.

In engines having more than one cylinder, one or more of the cylinders may be fitted with the steam valve for starting purposes as desired.

10 According to another form of the invention, an example of which is illustrated in Figure 2, the compression pressure may be temporarily reduced by discharging all or part of the charge of air before the end of the compression stroke. This is accomplished by mounting the rocking lever, C, which operates the air valve, A, upon an eccentric, S, which can be rotated. This eccentric is connected by an arm, T, fixed 20 thereon and a rod, U, to the control lever, K, so as to be operated at the same time as the rocking lever, F, of the steam valve. The other end of the rocking lever, C, is provided with a roller, V, which engages 25 with a cam, W, on the cam shaft. The back of the cam, W, is relieved so that during normal running the gear being as shown by the dotted lines, the roller, V, is not in contact, its path of motion relative to the cam 30 centre being shown by a chain dotted line.

When the control lever, K, is thrown over to the "starting" position the rocking lever, F, of the steam valve is brought into contact with the cam, I, so as to open the steam 35 valve and at the same time the fulcrum of the rocking lever, C, which operates the air valve is brought nearer to the cam shaft, as shown in full lines in Figure 2. In this position the roller, V, on the end of the 40 rocking lever follows closely the shape of the cam, which shape is such that the valve is held open, i. e. the closing of the air valve is delayed, until the end or near the end of what is usually the compression stroke. In 45 this manner the compression in the cylinder is regulated to the required amount.

Although the regulation of the pressure in the working cylinder has been described above as being controlled by the operation 50 of the air inlet valve, it is clearly to be understood that such regulation can also be effected by the operation of the exhaust valve, A', which is similar to the air valve, A, in the same manner as the air valve, A,

described with reference to Figure 2 of the 55 drawings.

The advantages of the starting devices made according to the invention are that the air compressor can be dispensed with, the cylinder can be maintained at a substantially higher temperature throughout the stroke than would be the case in starting with compressed air, the strains set up by variation of temperature are considerably reduced and the ignition of the first charge 60 is facilitated.

We wish it to be understood that the foregoing methods of carrying the invention into effect are by way of example only and that modifications thereof may be introduced without departing from the scope of the invention.

Having now described our invention, what we claim as new and desire to secure by Letters Patent is:—

1. A device for starting internal combustion engines working on the four-stroke cycle, comprising in combination a steam valve situated in the cylinder head, means for actuating said steam valve to admit steam on alternate revolutions of the engine, an air valve admitting air to the cylinder, means for educting gases from the cylinder, means for restricting the flow of air to said air valve during starting to reduce the compression on the compression stroke and a single instrumentality for bringing said steam valve and said restricting means into operation for starting, as set forth. 85

2. A device for starting internal combustion engines working on the four-stroke cycle, comprising in combination a steam valve situated on the cylinder head, means for actuating said steam valve to admit steam on alternate revolutions of the engine, 90 an air valve admitting air to the cylinder, a duct leading to said air valve, a throttle valve situated in said duct, an exhaust valve for educting gases from the cylinder and a single instrumentality for closing said throttle valve to reduce the compression on the compression stroke and for bringing said steam valve into operation, as set forth. 95

In testimony whereof we have signed our names to this specification.

CHARLES ALGERNON PARSONS.

STANLEY SMITH COOK.

HERBERT GEORGE KIMBER.
